ATTORNEY .

UNITED STATES PATENT OFFICE.

EVERT A. METCALF, OF FORBES, MISSOURI.

COMBINED VEST-POCKET PENCIL AND PEN HOLDER AND ELECTRIC LIGHT.

1,060,615.

Specification of Letters Patent.

Patented May 6, 1913.

Application filed April 13, 1912. Serial No. 690,619.

To all whom it may concern:

Be it known that I, EVERETT A. METCALF, a citizen of the United States of America, residing at Forbes, in the county of Holt 5 and State of Missouri, have invented certain new and useful Improvements in a Combined Vest-Pocket Pencil and Pen Holder and Electric Light, of which the following is a specification.

10 The object especially sought by me in this invention is to provide a device which while of more or less use to all classes of people will particularly be a convenience to physicians in writing prescriptions, lawyers, real 15 estate agents, notaries public and others who are frequently called upon to sign their names, or make memoranda, in rooms, or out of doors, where no light can be instantly procured or where the lights are burning 20 too dimly to be of service.

I accomplish my object by the mechanism illustrated in the accompanying drawings, in which,—

Figure 1 is a side elevation of the device 25 showing a case broken away, having a hinged end door, a battery, contact extensions and a flash light therein, a spring metal finger on the bottom of the case its adjustable end engaging with a push-button carrying 30 a contact point to engage with one of said contact extensions, and Fig. 2 is an elevation showing the opposite side of said case, a rigidly fastened pen or pencil holder thereon with spring clasps holding a pencil, 35 broken away, therein, said spring metal adjustable arm being in position on said push-button, the electrical parts in contact and the flash light shedding its rays in line with the pencil point.

40 Similar letters refer to similar parts both in the drawings and in the following description.

The device consists of an electrical battery 45 fitted into and readily removable from a casing B and provided with contact extensions A' and A''. The rear end of said casing is provided with a closure B' having a hinge b and a spring fastening b'. The

other end of the case is provided with a cone shape socket C. An electric light bulb D is 50 seated in said socket. One side of the case is provided with a rigidly attached holder E having spring clasps e e to hold a pen or pencil E' firmly in their grasp. The opposite side of the case at its closure end has a 55 spring metal strip or arm F rigidly fastened to the case at one end and adapted to engage with the outside of an upper vest-pocket and hold the case within said pocket. Near the forward end of the top of the case there 60 is a perforation H through which a push-button I operates upon spring metal strip J said strip being attached at one end to the interior of the case the spring end thereof being provided with a point which when 65 pressed by said button contacts with the contact extension A'. A metal finger is pivotally attached at its rear end to the top of said case. When it is desired to use the pen or pencil, push-button I may be held down 70 with one of the fingers of the hand holding the case or the other unattached end of metal finger L may be swung over push-button I retaining its pressure upon the push-button as long as the rays of the flash light are 75 desired to rest upon the object being examined or on the paper on which the pencil or pen may be in use.

What I claim and desire to secure by Letters Patent, is,—

As an article of manufacture, a pocket battery-lamp having a push button, a casing for said lamp provided on one side with a resilient securing strip, and on another side with an article-holding clasp, and also having a spring metal strip pivoted to said casing and adapted to be swung over the push button to hold the battery circuit closed; substantially as described.

In testimony whereof I affix my signature 90 in presence of two witnesses.

EVERETT A. METCALF.
